UNITED STATES PATENT OFFICE.

PETER H. NILES, OF BOSTON, MASSACHUSETTS.

IMPROVED BROOM-CLASP.

Specification forming part of Letters Patent No. 55,345, dated June 5, 1866.

To all whom it may concern:

Be it known that I, PETER H. NILES, of Boston, in the county of Suffolk and Commonwealth of Massachusetts, have invented a new and useful Improvement in Protectors or Holders for Brooms; and I do hereby declare that the following is a full and exact description thereof, reference being had to the accompanying drawings, and to the letters of reference marked thereon.

To enable others skilled in the art to make and use my invention, I will proceed to describe its construction and operation.

In the common house-broom as at present used it is found desirable to preserve the broom and increase its durability by confining and supporting the wisps of the broom below the usual permanent fastening by means of some device which can be removed or adjusted as the broom is worn up. The purpose of my invention is to accomplish this by a simple, cheap, and effective device.

Upon the accompanying drawings, Figure 1 represents a perspective view of my invention. Fig. 2 represents an elevation of the same. Fig. 3 represents a plan of the same. Fig. 4 represents a view of the spring-pin.

I construct the protector of a single wire, at the apex of which are formed two coils of a spiral spring. (Marked *a a*.) These coils effect a double purpose—first, forming a spring to

enable the protector to yield to the spread of the broom; second, one of these coils forms an eye, into which is linked the spring-pin, as shown in Fig. 2; the other forms a rest into which one or both of the points of spring-pin may be inserted, as shown in Fig. 1, forming, by the curves *e e*, struck in said pin, a lock. There is also sufficient spring to the vertical portions of the protector *b b b b* to make it clasp the sides and at the same time yield to the bending motion of the broom in use.

The curved portions *c c c c* of the wire inclose the broom and derive their spring from the coils of the spiral spring *a a*, and the ends of the wire are here joined. The spring-pin, as shown in Fig. 4, is formed with an eye, *d*, which is permanently linked into one of the coils *a*. There are two curves, *e e*, in the points of the pin which pass through the broom and lock into the opposite coil, either as shown in Fig. 3 or by passing both points through the coil. The object of this pin is to secure the protector in a proper position.

I claim—

The spring-pin, in combination with the protector, for the purpose and in the manner substantially described.

P. H. NILES.
